UNITED STATES PATENT OFFICE.

ALBERT G. WADE, OF ELKHART, INDIANA.

PLATE AND BASE FOR PRINTING.

SPECIFICATION forming part of Letters Patent No. 530,371, dated December 4, 1894.

Application filed June 8, 1894. Serial No. 513,911. (No model.)

To all whom it may concern:

Be it known that I, ALBERT G. WADE, a citizen of the United States, and a resident of Elkhart, in the county of Elkhart and State of Indiana, have invented certain new and useful Improvements in Plates and Bases for Printing; and I do hereby declare the following to be a full, clear, and exact description of the invention, such as will enable others skilled in the art to which it appertains to make and use the same.

This invention relates to plates and bases for printing, and has for its object to provide an entire solid and equal foundation for all parts to form a perfect, rigid and even impression throughout its entire surface and wherein the plate can be taken directly off its base without removing the base from the form in order that another plate may be substituted.

With these and other objects in view, the invention consists of the construction and arrangement of the several parts which will be more fully hereinafter described and claimed.

In the drawings:—Figure 1 is a perspective view of a base and plate embodying the invention. Fig. 2 is an enlarged sectional view on the line X—X of Fig. 1. Fig. 3 is an enlarged sectional view on the line y—y of Fig. 1.

Similar numerals of reference are employed to indicate corresponding parts in the several views.

Referring to the drawings, the numeral 1 designates a base which is of the ordinary form and having an upper flat smooth surface and at one end thereof is secured a metallic plate 2, preferably of brass, which is formed of the same width as the base and at the center thereof is a recess, and on each side thereof are upwardly projecting flanges 3 having an inner beveled wall 4, the said flanges standing above the surface of the base. To the opposite end of the base is applied a plate 5 of the same conformation, made with a central recess 6 and opposite end flanges 7 whose inner surfaces are beveled as at 8, the said end flanges 7 standing opposite and of equal extent to the flanges 3 on the plate 2, while the recess 6 in the plate 5 has its terminating side walls in line with the outer sides of the recess in the plate 2.

The plate 9 is applied to the flat surface of

the base and at one end are side recesses 10 with beveled walls and opposite shoulders 11, the said recesses being adapted to fit against and the plate be held down by the flange 3. 55 The opposite end of the plate 9 is similarly formed with opposite side recesses 11* with beveled walls 12 adapted to engage the inner beveled walls of the side flanges 7 of the plate 5, the recess 6 of the said plate 5 being 60 engaged by a tongue 13 formed on the plate 9. By this means the plate 9 is held in removable connection with the base firmly against a smooth surface and may be removed at will without the use of a mallet or 65 injury of the plate or base while the electro-type and its base are held in the form. A further advantage of this device is that a flat surface is presented with an even printing foundation and by the use of the device there 70 is considerable economy in time and cost.

The plate 5 has connected thereto a pair of bolts or pins 14, which are movably attached to one of the cross ribs or a projection of the base 1, the said bolts or pins being long 75 enough to permit the plate 5 to move backward from and upward against the end of the base in the process or operation of applying or removing the electro-type plate and preventing the plate 5 from becoming lost and 80 also holding it in convenient operative position.

What is claimed as the invention is—

1. In a device of the character set forth, the combination with a base having a smooth 85 surface and plates at the opposite ends thereof, each of which is provided with a central recess and outer flanges having inner beveled faces, of a printing plate formed at each of its ends with a projecting tongue and with 90 outer recesses having beveled edges, the said tongues fitting the recesses in the said plate, as and for the purpose described.

2. In a device of the character set forth, the combination with a base having a smooth 95 surface and plates at the opposite ends thereof, one of which is rigidly secured to said base and the other loosely secured thereto, each of the said plates being provided with a central recess and outer flanges having inner beveled faces, of a printing plate formed at each of its ends with a projecting tongue and with 100

outer recesses having beveled edges, the said tongues fitting the recesses in the said plates, as and for the purpose described.

3. In a device of the character set forth, the combination with a base having a smooth surface and plates at the opposite ends thereof, one of which is rigidly secured to said base and the other secured thereto by means of bolts passing through a portion of the said base which give the said plate a limited movement away from said base, each of the said plates being provided with a central recess and outer flanges having inner beveled faces,

of a printing plate formed at each of its ends with a projecting tongue and with outer recesses having beveled edges, the said tongues fitting the recesses in the said plates, as and for the purpose described.

In testimony whereof I have signed this specification in the presence of two subscribing witnesses.

ALBERT G. WADE.
